UNITED STATES PATENT OFFICE

ARTHUR W. BURKS, OF DECATUR, ILLINOIS

METHOD OF PUMPING AND SYSTEM THEREFOR

Application filed August 23, 1929. Serial No. 387,990.

The present invention relates to pumps and pumping systems.

An object of the invention is to provide an improved pumping method and system for practicing the method; also to provide a pump of improved construction, which although of general application, is particularly adapted for practicing my improved method, and for use in connection with the pumping system herein disclosed.

The method and system are illustrated and described in connection with a pump of the rotary type, a pump of this character being described, for example, in my Patent 1,686,549, granted October 9, 1928. Pumps of this type are generally recognized as shallow-well pumps, and their lifting capacity does not usually exceed approximately thirty two (32) feet.

An object of the present invention is to provide a method and system which, when employed in connection with a pump of this type, will increase its lifting capacity and adapt it for deep-well pumping.

Another object of the invention is to provide a system and method for pumping which is simple, comparatively inexpensive, and which, since it comprises few mechanical or moving parts, is reliable in operation.

A still further object is to provide a pumping system and method of high capacity which may be varied throughout a very wide range with little change in the construction or size of the parts.

The foregoing and other objects of the invention, as well as constructional features of the system and pump, will become clearer as the description proceeds in connection with said preferred embodiments disclosed in the accompanying drawings, wherein,

Figure 1 is a somewhat diagrammatic outline of the pumping system.

Figure 2 is a cross sectional view on the line 2-2 of Figure 1 of one of the two pumps employed.

Figure 3 is a view of one of the system units which is located within the well.

Figure 4 is a side view of the unit shown in Figure 3 with part broken away.

Referring to the drawings for a more de-

tailed description, the system is shown in Figures 1 and 5; it comprises a downward pressure-feed conduit 10, through which a stream of fluid, preferably water, may be directed into the lower end of a housing 11. 55 The stream passes under pressure upwardly through the housing, as indicated by the arrows 12 (Figure 4) along a path substantially tangential to an annular chamber 13. At its entrance end the housing 11 is provided with a tapered passage 14 adapted to increase the velocity of the fluid as it travels past the chamber 13; and at the upper end of the housing there is formed a gradually enlarging passage 14' adapted to decrease the 65 velocity, but increase the pressure. Fluid, such as water is forced downwardly under suitable pressure in the pipe 10, so that it will travel upwardly through the passage and housing 11 at relatively high velocity. 70 Any suitable means may be provided for creating this fluid stream, and means suitable for this purpose will be later described.

The passage in the housing communicates intermediate the tapering portions 14, 14' and through a port located between the points 16 and 17 with the chamber 13. A body of water introduced into the chamber 13, for instance, from the fluid stream will have imparted thereto by the stream traveling 80 through the housing, a whirling motion, which will continue as long as the fluid of the stream is maintained in motion through the housing in tangential relation to the water within the chamber 13. There is thus 85 formed in the chamber 13 a whirlpool, the speed of which will depend largely upon the velocity of the fluid in the stream passing through the housing 11.

The chamber 13 is in communication, preferably at the center 18 of the whirlpool, with the body of fluid B (Figure 1) to be pumped, a pipe 19 serving this purpose. The pipe may, if desired, be provided with a foot valve F' (Figure 1) of suitable construction.

The rapid motion of the whirling body of water in the chamber 13, which may whirl about a vertical axis, if desired, instead of the horizontal axis shown in the drawings, sets up a very strong suction, and the same has been 100

found sufficient to lift water at least twenty (20) feet above the level of the body B in a well. If the suction pipe 19 is filled with air, the whirlpool and the aspirator injector water passing from port 16 to port 17, draws out this air which passes through the pipe 10 with the water. The centrifugal action set up in the whirlpool will separate the air therefrom, causing the same to pass into the stream being forced through the housing 11. When the pipe 19 is cleared of air, the water or other fluid to be pumped will be drawn into the chamber 13, and as the whirling body in this chamber increases in volume, the fluid pumped will be conducted off, in the present instance with the stream forced through the housing 11. The fluid pumped is caused to enter the traveling stream both by the centrifugal action of the whirling body, which causes the excess fluid to pass through the port between the walls 16, 17, and also by the injector action of the stream as it passes this port. After the fluid enters the stream within the housing 11 from the chamber 13, it makes room in the chamber for additional fluid which is continuously being introduced in the whirlpool at its center and taken off by the tangentially related stream.

For practicing this method of pumping, any means may be used which will maintain the desired pressure and velocity in the pipes 10, 10'. For example, in Figure 1 the system embodies two pumps of the rotary type, disclosed in my Patent 1,686,549, granted October 9, 1928. In the remaining views I have shown a number of single pump units of the same general type which may be employed instead of a plurality of pumps.

Referring to Figs. 1 and 2 the pump 20 may serve as a pressure pump for forcing downwardly fluid under pressure in the pipe 10, and the pump 21 as a suction pump for assisting in lifting the fluid through the pipe 10' which communicates with the upper end of the well unit or housing 11. The pump 20 may be of considerably smaller capacity than the pump 21 and may receive its fluid from a storage tank 22 through a suitable connection 23 which returns to the pump 20 fluid in a considerably smaller volume than is introduced into the tank from a discharge pipe 24 of the pump 21. The pumps 20, 21 are of identical construction, and as illustrated in Figure 2, each comprises a casing section 25 having a raceway 26 which has one end communicating with an inlet chamber 27 and the other end communicating with an outlet chamber 28 having its wall thinned or bevelled as at 28' where the water enters the chamber. Water entering the raceway 26 is conducted around the same by the rotor 29, which is provided with a plurality of impelling buckets 30, as described in my patent above mentioned.

Further description of the pump construction is unnecessary, since the same is virtually

identical with that in my patent above identified, except that in addition to the outlet chamber 28 which maintains a whirling body of fluid, there is provided a corresponding inlet chamber 27 in each pump. As will be understood, the fluid forced downwardly in pipe 10 passes upwardly through the housing 11 where it entrains to the pumped liquid or fluid from chamber 13. The pumped fluid and that of the stream continues on to pump 21, from which it is discharged into a storage tank 22. A certain portion of this fluid, sufficient to maintain a stream of the desired volume in the pipe 10, returns to the pump 20, from which it is forced through the pipe 10 to the well unit or housing 11. The two pumps 20, 21, may be driven in any suitable manner; in Figure 1 they are shown side by side, although they may be disposed in tandem relation so as to be actuated by a common drive shaft, as well as a common rotor.

It will be understood that although the system is illustrated as employed in association with pumps of the rotary type, it may be used in connection with other types of pumps. Obviously, the method, the system, and the pumps described, may be modified considerably without departing from the invention, the essential features of which are set forth more definitely in the following claims.

I claim:

1. The method of pumping, which consists in forming a stream of liquid, maintaining a whirling body of liquid by said stream, utilizing the whirling body to lift from a lower elevation thereinto fluid to be pumped, and taking off the pumped fluid from above said body as the body increases in volume.

2. The method of pumping, which consists in forming a stream of liquid, maintaining a whirling body of liquid on a horizontal axis by said stream, utilizing the whirling body to lift from a lower elevation by suction thereinto fluid to be pumped, and taking off the pumped fluid from above said body as the body increases in volume.

3. The method of pumping, which consists in forming a stream of liquid, maintaining a whirling body of liquid by directing the said stream along a path tangential to the whirling body, utilizing the whirling body to lift from a lower elevation thereinto additional fluid to be pumped, and taking off the pumped fluid from above said body as the body increases in volume.

4. The method of pumping, which consists in forming a stream of liquid, maintaining a whirling body of liquid by the said stream, utilizing the whirling body to suck thereinto at approximately its center additional fluid to be pumped, and taking off the pumped fluid from said body as it increases in volume.

5. The method of pumping, which consists in forming a stream of liquid, maintaining a

whirling body of liquid by the said stream, utilizing the whirling body to suck thereinto additional fluid to be pumped, and taking off into said stream the pumped fluid from

5 said body as the body increases in volume.

6. The method of pumping, which consists in forming and maintaining a whirling body of liquid by a stream of liquid, utilizing the whirling body to lift thereinto additional

10 fluid to be pumped, introducing the pumped fluid from said body into said stream and conducting the said fluid off in said stream.

7. The method of pumping, which consists in forming and maintaining a whirling body of liquid by a stream of liquid, utilizing the whirling body to lift thereinto from a lower elevation additional fluid to be pumped, and centrifugally taking off the pumped fluid from said body as it increases in volume.

20 8. The method of pumping, which consists in forming and maintaining a whirling body of liquid by a stream of liquid substantially tangential to the whirling body, utilizing the whirling body to lift from a lower elevation

25 thereinto at approximately its center additional fluid to be pumped, and taking off the pumped fluid from said body as it increases in volume.

9. The method of pumping, which consists in forming and maintaining a whirling body of liquid by a stream of liquid substantially tangential to the whirling body, utilizing the whirling body to lift from a lower elevation

35 thereinto at approximately its center additional fluid to be pumped, and by the action of said stream taking off the pumped fluid from said body as it increases in volume.

10. The method of pumping, which consists in forming and maintaining a whirling body of liquid by the action of a stream of liquid substantially tangential to the whirling body and adapted to act as an injector upon said body, utilizing the whirling body to lift from a lower elevation

45 thereinto at approximately its center additional fluid to be pumped, and by the centrifugal action of said body and the injector action of said stream taking off the pumped fluid into said stream from said body as it increases in

50 volume.

11. The method of pumping, which consists in forming and maintaining a whirling body of liquid by the action of a stream of liquid substantially tangential to the whirling body, utilizing the whirling body to lift from a lower elevation

55 thereinto at approximately its center additional fluid to be pumped, and continuously taking off the pumped liquid from the periphery of said

60 body into said stream.

12. The method of pumping, which consists in forming and maintaining a whirling body of liquid by the action of a stream of liquid, utilizing the whirling body to lift

65 from a lower elevation thereinto additional

fluid to be pumped, taking off from said body into said stream as it increases in volume the pumped fluid, and conducting the fluid away in said stream.

13. In a pumping system, means for producing a fluid stream, means for creating by said stream a whirling body of liquid, means for placing said whirling body in communication with a body of fluid to lift the same from a lower elevation, and means for taking off pumped fluid from said body as the body increases in volume.

70 14. In a pumping system, means for producing a liquid stream, means for creating by said stream a whirling body of liquid, means for placing said whirling body in communication with a body of liquid to lift the same from a lower elevation, and means for taking off pumped fluid from said body as the body increases in volume.

80 15. In a pumping system, means for producing a fluid stream, means for creating by said stream a whirling body of liquid with the adjacent path of the stream substantially tangential to said body, means for placing said whirling body in communication with a body of fluid to lift the same from a lower elevation, and means for taking off pumped fluid from said body as the body increases in volume.

85 16. In a pumping system, means for producing a fluid stream, means for creating by said stream a whirling body of liquid, means for placing said whirling body at substantially its center in communication with a body of fluid to lift the same from a lower elevation, and means for taking off pumped fluid from said body as the body increases in volume.

90 17. In a pumping system, means for producing a fluid stream, means for creating by said stream a whirling body of liquid with the adjacent path of the stream substantially tangential to said body, means for placing said whirling body at substantially its center in communication with a body of fluid to lift the same from a lower elevation, and means for taking off pumped fluid from said body above the same as the body increases in volume.

95 115 18. In a pumping system, means for producing a fluid stream, means for creating by said stream a whirling body of liquid with the adjacent path of the stream substantially tangential to said body, means for placing said whirling body at substantially its center in communication with a body of fluid to lift the same from a lower elevation, and means for taking off pumped fluid into said stream from said body as the body increases in volume.

100 120 19. In a pumping system, means for producing a fluid stream, means for creating by said stream a whirling body of liquid with the adjacent path of the stream substantially

tangential to said body, means for placing said whirling body at substantially its center in communication with a body of fluid to lift the same from a lower elevation, and 5 means for taking off pumped fluid into said stream from the periphery of said body above the same as the body increases in volume.

20. A pump comprising a body having a circular chamber arranged in a vertical plane, an inner conduit communicating with 10 the axis of said chamber, said body having an inner port converging to tangentially communicate with the bottom of said chamber, said body having an outlet port diverging upwardly and tangentially from said chamber opposite said tangential inlet, and 15 conduits connected to said tangential inlet and outlet for conducting a stream of fluid under pressure and to create in said circular chamber a whirling body of fluid to lift 20 fluid first from said inlet conduit and introduce it into the axis of said whirling body of fluid.

In testimony whereof I have hereunto set
25 my hand.
